UNITED STATES PATENT OFFICE.

JACOB SCHIRATWIESER, OF BROOKLYN, NEW YORK.

DESIGN FOR METALLIC LATH.

SPECIFICATION forming part of Design No. 25,525, dated May 19, 1896.

Application filed December 11, 1895. Serial No. 571,836. Term of patent 7 years.

To all whom it may concern:

Be it known that I, JACOB SCHIRATWIESER, a citizen of the United States of America, and a resident of Brooklyn, in the county of Kings and State of New York, have invented a certain new and original Design for Metallic Lath, of which the following is a specification, reference being had to the accompanying drawings, forming part of the same, in to which—

The article is a metallic lath, an article now largely used, and formed in strips of varying widths and indefinite lengths, usually oblong in its general outline; but my design has reference rather to its face, and consists in a lath with a series of openings or representations of openings, oblong in form, and a strip or corrugation bordering the side of the panel, which strip is of a different elevation or has the appearance of being at a different elevation from the main plane of the lath, and these are the essential characteristics of the design—a substantially plane face with what appears to be oblong openings in said face and a bounding-strip which appears to be arranged at a different elevation from the main plane of the face of the lath.

What I claim as my invention, and desire to secure by Letters Patent, is—

The design for metallic lath, substantially as herein shown and described.

In testimony that I claim the foregoing as my invention I have signed my name, in presence of two witnesses, this 2d day of December, 1895.

JACOB SCHIRATWIESER.
